METHOD AND APPARATUS FOR MAKING RIP SEALS FOR PACKAGES

Heinrich Schünemann, Berlin-Spandau, Germany, assignor, by mesne assignments, to Haus Neuerburg, Köln Zweig der H. F. and Ph. F. Reemstsma, Cologne, Germany, a limited partnership of Germany

Application January 9, 1936, Serial No. 58,364
In Germany April 20, 1935

3 Claims. (CL 216—30)

This invention relates to a method and means for producing an air and moisture-proof rip seal for packages, more particularly cigarette boxes.

In order to produce such a seal, it is known to 5 unwind a strip from a reel, pass it by a glueing device so as to apply an adhesive to one side thereof and to cause the strip to adhere around the joints of the package.

The gist of the invention resides in the fact that 10 after applying the glue, a narrower ripping strip or spaced ripping cords are arranged on the adhesive side of the strip and that a ripping tongue is formed after applying the ripping strip to the sealing strip. The layer of glue is also covered 15 on one end by a strip of paper and this part of the strip is provided with slots on both sides of the ripping strip or ripping cords.

The invention is illustrated by way of example 20 in the accompanying drawings in which:

Figure 1 is a front view of the closed air and 25 moisture-proof rip seal for a cigarette box or package.

Figure 2 is a similar view showing the start of 30 the opening operation.

Figure 3 is an elevation and Figure 4 a plan view 35 of a machine for carrying out the method of providing the composite strip.

Figure 5 is an enlarged view in elevation of the 40 means for covering the glue layer at an end of the strip and for forming slots therein.

Figure 6 is a side view of the apparatus shown 45 in Figure 5.

Referring to Figures 1 and 2 it is to be noted 50 that the seal is formed from a foil strip 1, on the adhesive side of which a narrower ripping strip or several cords 2 are arranged which may be embedded in the adhesive layer. The overlapping end 1b of the strip 1 is partially covered by a non-glued strip or piece of paper 3 so that the covered 55 part cannot stick to the portion 1a of the strip 1. Slots 4 are provided in the end 1b adjacent the edges of the seal strip or in the vicinity of the ripping cords and by means of these slots a tongue is formed for ripping the seal in a manner as shown in Fig. 2.

According to the invention, the working method 60 for producing the seal resides in the fact that the seal strip provided with the ripping strip or the ripping cords is covered on the overlapping end and on the glued side with a paper strip cut from a continuous roll and provided with slots on both sides of the ripping strip or ripping cords after which it is severed from the continuous strip.

The means for carrying out such a method is 65 shown in Fig. 3 and includes a reel 6 from which

the strip 1 is drawn. The seal strip 1 removed from the reel 6 is moved over a glue wheel 7 so that an adhesive is applied to one side. The glueing apparatus comprises a glue container 8 and a nozzle 9. The glue wheel 7 rotates with the periphery adjacent the orifice of the nozzle 9. In order that the glue will not be applied to the outermost edges of the strip 1 so as to protrude laterally over the edges of the strip and soil the package, the edges of the strip 1 are covered by covering 10 members 10, Fig. 3, whereby narrow edges of the seal strip remain free of glue.

The glue-applying roller 11 may be adjusted for 15 the purpose of regulating the thickness of the layer of glue.

The glue container 8 may be swung about the 20 shaft 18 of the glue wheel 7 as shown by dot-and-dash lines in Figure 3. The glue wheel 7 is also mounted in bearing arms and adapted to swing on pivots 19 in order that it may be moved into 25 the position shown by dot-and-dash lines in Figure 3. This arrangement permits easy cleaning of the glue-applying apparatus.

After the strip 1 has passed the glueing apparatus, it enters a drying device 20, which has 25 the form of a vertical chamber. In this drying chamber, rollers 21 are arranged, Figs. 3 and 4, which are driven from the main shaft of the machine. From the lower rollers 21, the seal strip 30 passes over an upper guide roller 22. The strip is conducted in several loops through the chamber 20 whereby rapid and efficient drying is ensured. The drying process or the volatilization of the 35 glue solvent may also be accelerated by arranging heating devices 23 in the drying chamber 20.

It is to be noted that the strip 1 always passes 40 over the guide rollers crosswise so that the glued side is located externally. After passing out of the drying chamber 20, the strip 1 passes over a tensioning or equalizing roller 24, carried by a 45 rocking lever, to a roller 25.

The ripping cords 2 are then applied to the 50 glued side of the strip. These cords are removed from reels 26 which are rotatably mounted on the machine frame. The cords are held apart by a 55 guide member 27 to the extent required for the ripping width and the cords are pressed onto the glue layer of the strip 1 by means of a weighted roller 28.

The stepwise advance of the strip 1 with the 60 ripping cords embedded on glued side thereof, see Figure 4, is effected by pliers or gripping means 31 which are opened and closed periodically and reciprocate over a distance equal to the length of one seal strip. The pliers 31 coop- 65

erate with a latch 30 and a guide 29 for the strip 1 in such a manner that when the foremost piece 5 of the strip (for the sealing of one package or box) has been cut off, the latch 30 presses the seal strip resiliently against the guide 29 so as to prevent the strip 1 from sliding back under the action of the swinging equalization roller 24.

When a severed piece of the strip 1 is to be laid 10 around a package, the strip 1 must be advanced stepwise while the guide rollers 21, which move the strip 1 from the reel 6 through the glueing apparatus and the drying device, rotate continually. The equalizing roller 24 swings up and down whereby the seal strip from the glueing apparatus to the guide 29 is kept under tension.

When the pliers 31 are moved in the direction 15 of the arrow 39, they engage, at the end of the stroke, the free end of the strip 1 and advance it to the extent of a new sealing length. Shortly before the end of the stroke, a paper strip 3, Figures 4, 5 and 6, for covering the glue layer 20 of the end of the strip 1 is advanced parallel to the strip 1 from a reel 46 shown in Fig. 3. This movement of the paper strip 3 is effected by 25 a driving pulley or roller 41 shown particularly in Fig. 5. An endless belt 43 passes around the roller 41 and around a pulley 42 spaced therefrom. The roller 41 may for instance be driven by means of a ratchet wheel 44 shown in Fig. 6 30 and a pawl carried by a lever 45.

The strip 3 drawn from the reel 46 passes 35 through a guide 47 which is rotatably mounted on a pivot 48. This guide normally occupies the position shown in full lines in Figure 5. Immediately before the pliers 31 close and a fresh seal strip section is advanced the guide 47 is swung into the position shown in dotted lines and the paper strip 3 is fed forward. Thereupon the shears 49 close which movement may be effected by a cam 40 disk 50 shown in Fig. 3. The strip section to be placed on the package is thereby cut from the continuous strip 1 and the paper strip 3 applied on the glued side of its end is simultaneously 45 cut. As shown in Fig. 5 a press member 51 is mounted on one leg of the shears 49 which, during the cutting operation presses the paper strip 3 firmly against the glued face of the strip 1.

A pair of cutters 57 are moved by a slide 56 towards the end of the strip in the direction of the 50 arrow 58, Figure 5. Before the pair of cutters 57 touch the seal strip, a spring-influenced roller 59 contacts the piece of paper 3. The cutters 57 then provide slots in the end of the severed strip 1. The cutting operation takes place when 55 the severed strip section lying in the path of the packages 52 to be sealed is moved along by the package 52, Figure 4, in the direction of the arrow 53. The two slots 4, Figure 1, are thereby

formed which extend along the two edges of the piece of paper 3. These slots have for their object to free one end of the strip 1 or that part thereof which is provided with the piece of paper 3 and to facilitate the gripping of the overlapping end. The tongue provided in the overlapping end is called the "grip". When it is desired to open the package, a pull is exerted on the grip whereby the strip 1 is torn along the joint by the ripping cords 2.

After the strip section for sealing a package has been severed from the roll, it is carried along with the package or box 52 in the direction of the arrow 53 whereupon the seal strip is arranged around the opening joint of the box in a known 15 manner.

I claim:—

1. A method of producing a rippable strip adapted for sealing packages which comprises, removing an air and moisture-proof strip from a 20 roll thereof, applying an adhesive to one side of the moving strip, embedding a narrower ripping strip in the adhesive face of the moving strip, and covering a portion of the strip on the adhesive face with a strip of paper, cutting slots 25 along both edges of the ripping strip and thereafter severing the strip adjacent the paper covered end.

2. In apparatus adapted to complete the formation of a package sealing strip having a narrower ripping strip adhesively attached to one face thereof to provide a composite rippable sealing strip for a package, means for intermittently moving the composite strip, a reel adapted to hold a continuous paper strip wound thereon, 30 means for feeding forward said paper strip, a cutting device arranged in the path of movement of the composite strip, movable means for guiding the paper strip from the reel to a position adjacent the adhesive coated face of the first 35 mentioned strip and adjacent the cutting device so as to cover a portion of the adhesive coated face, means associated with said cutting device for urging an end portion of the paper strip against the adhesive coated face of the composite strip, and said cutting device being adapted to sever the composite strip and the paper strip whereby the end portion of the composite strip is covered on the adhesive coated face by the severed portion of the paper strip.

3. Apparatus according to claim 2 characterized by the fact that a slide member having a pair of cutters is moved simultaneously with the cutting device towards the composite strip and slots are cut in the end of the strip along both sides 55 of the ripping strip.

HEINRICH SCHUNEMANN.
